UNITED STATES PATENT OFFICE

JOHN A. CONNOLLY, OF NEW YORK, N. Y.

DESIGN FOR A STATUETTE OR THE LIKE

Application filed December 15, 1931. Serial No. 42,095. Term of patent 3½ years.

To all whom it may concern:

Be it known that I, JOHN A. CONNOLLY, a citizen of the United States, residing at New York, in the county and State of New York, have invented a new, original, and ornamental Design for a Statuette or the like, of which the following is a specification, reference being had to the accompanying sheet of drawings, forming part thereof.

Fig. 1 is a rear view of my new design for a statuette or the like.

Fig. 2 is a side view, and

Fig. 3 is a front view thereof.

I claim:

The ornamental design for a statuette or the like, as shown.

JOHN A. CONNOLLY.
